UNITED STATES PATENT OFFICE.

WILLIAM THOMAS JAMES, OF CHICAGO, ILLINOIS.

MAILING-RECEPTACLE.

1,363,252.

Specification of Letters Patent. Patented Dec. 28, 1920.

Application filed December 27, 1915. Serial No. 68,689.

To all whom it may concern:

Be it known that I, WILLIAM THOMAS JAMES, a citizen of the United States, and a resident of Chicago, in the county of Cook and State of Illinois, have invented certain new and useful Improvements in Mailing-Receptacles, of which the following is a specification.

The present invention relates to mailing receptacles, and more particularly to receptacles employable for the purpose of transmitting money through the mails. It has special reference to the provision of an improved structure whereby a mailing receptacle, including, when desired, a money carrier, may be transmitted through the mail as "open" matter, subject to inspection by the post office officials, and bear a relatively lower rate of postage, and which, when 20 coins or bills have been inserted in the money carrier, may be re-mailed under the same cover, securely sealed against inspection, or loss of the contents, the structure bearing at such a time a relatively higher 25 rate of postage.

The principal objects of the present invention are the provision of an improved article of the class specified which may carry on its unexposed surface a suitable 30 "form" letter, or other advertising matter, and on the opposite or exposed surface one or more address portions which, alternately, when exposed, may be used for first mailing by the sender, and then returning the 35 receptacle to the sender; the provision of an improved structure of the nature specified which may be sent out in the first instance "open" and returned either "open" or "sealed"; the provision of an improved 40 form of money carrier for the purpose specified, and generally, the provision of an improved form of money carrying mailing receptacle which will not only hold the coins and other money more securely, but also be 45 manufactured more cheaply, as well as transmitted through the mails more inexpensively than others known to me, together with such further objects as may hereafter appear.

In attaining the objects referred to, together with certain additional benefits and advantages to be below disclosed, I have provided a structure one embodiment of

which is illustrated in the accompanying drawings, wherein:

Figure 1 is a plain view of a preferred form of the device;

Figs. 2, 3 and 4 are, respectively, a plan view, a perspective view and a transverse sectional view of the device of Fig. 1, illustrative of the steps of closing the receptacle when it is intended that the same shall be mailed out in "open" condition;

Figs. 5, 6, 7 and 8 are plan views, and Fig. 9 a cross-sectional view, of the device of Figs. 1 to 4, showing the consecutive steps of folding the receptacle preparatory to returning it to the original sender in "sealed" condition; and

Fig. 10 is an enlarged vertical cross-section of a detail of construction of one of the coin-carrying elements.

Referring now more particularly to Fig. 1, it will be noted that in carrying out my invention in the form here shown, I employ a sheet of paper, or other suitable material, 10, which is preferably scored for holding at the points indicated at 11 and 12, the corners at each side being cut away, as indicated at 13-13, and notches provided, as indicated at 14-14, in order to provide oppositely disposed flaps, as indicated at 16, 17, 18, 19, 20, 21, the structure thus formed when folded providing three fold portions, including a central portion 22, and end portions 23 and 24 (see Fig. 3). The flaps 20 and 21 are preferably given an adhesive surface, as indicated at 25, 26. An adhesive may, if desired, likewise be applied to the flaps 18 and 19, as indicated at 27 and 28, when such flaps are employed, and when it is desired to retain the coin carrier 29 permanently in position on the sheet 10 so as to form a pocket for the reception of paper money, or a check or money order, an adhesive may be applied to the flaps 16 and 17, as indicated at 30 and 31.

The coin carrier 29 comprises preferably a suitable sheet of cardboard, or like material, which has a suitable number of punched-out portions, as indicated at 32, 33, against which the edges of the coin abut, and a number of slits 34 forming holding strips 35, 36, and an intermediate holding strip 37 for gripping the coin therebetween.

In the use of the device the communica-

tion may be printed on the surface A, the address of the sender on the surface B, and the address of the addressee written on the surface C.

5 The coin carrier 29 is placed on the sheet 10, as shown in Fig. 1. Then, as shown in Fig. 2, the flaps 18 and 19 (where such are used, for example, to strengthen the device) are turned inward, as are also the flaps 20 10 and 21, as shown in Fig. 2. The portion 24 is then folded against the portion 22, as shown in Fig. 3, and the portion 23 is next brought over against the portion 24, and finally the flaps 16 and 17, respectively, 15 are tucked into position between the flaps 18—20 and 19—21, as shown in Fig. 4, the the structure thus presented being mailable as matter open to inspection at a relatively low rate of postage.

20 When, however, the addressee desires to return the structure with the coin-carrier 29 sealed against inspection, he may place it against the portion 23, and by moistening the adhesive applied to the surface opposite to that shown in the drawing, and contained between the dotted line 38 and the margin of the carrier 29 form a bill carrying pocket, then fold down the flaps 16 and 17, next fold over the members 29 and 23 25 against the surface 22, seal the flaps 18 and 19 against the outer surface of the portion 23, as shown in Fig. 7, then fold over the surface 24 against the surface 23, thus sealing, but not destroying the address of 30 the original addressee, now the remitter, and disclosing the address of the first sender, now the addressee, as shown in Fig. 35 8. The flaps 20 and 21 may now be sealed in position fully securing the contents of 40 the envelop structure thus formed against inspection, such structure being shown in longitudinal cross-section in Fig. 9.

Reverting now more particularly to Fig. 1, it will be observed that by the employment of the form of coin carrier here shown, 45 I am able to utilize the strips 35 and 36 which contact with one surface of the coin, and a strip 37 contacting with the opposite surface of the coin to firmly grasp the coin

in position, the form of the cut-outs 32 being such as to hold the coin against lateral movement, there being, of course, sufficient pliability in the strips 35, 36, 37 to enable enough distortion of such strips to permit the slipping of the coin therebetween and 55 into the socket formed by the cut-outs 32, as is clearly shown in Fig. 10.

Having thus described my invention and illustrated its use, what I claim as new and desire to secure by Letters Patent is the 60 following:—

1. A mailing receptacle having three consecutive folds, each fold having a pair of laterally projecting flaps all having adhesive on the same side when the receptacle is 65 unfolded, each pair to be used successively as sealing means whereby the receptacle may be held in closed position.

2. A mailing receptacle having three consecutive folds, one of said folds being provided with a pair of laterally projecting flaps adapted for insertion between two of said fold portions whereby the receptacle may be held in closed position without preventing withdrawal of the flaps for inspection of the contents of the receptacle, said other two folds each having a pair of laterally projecting flaps, all of said flaps being provided on the same side when the receptacle is unfolded with an adhesive portion adapted to engage an opposite fold portion and thereby seal the receptacle against 75 inspection.

3. A mailing receptacle having three consecutive folds, each fold having a pair of laterally projecting flaps, all of said flaps being provided on the same side when the receptacle is unfolded with an adhesive portion adapted to engage an opposite fold portion and thereby seal the receptacle 80 90 against inspection.

In testimony whereof I have hereunto signed my name in the presence of the two subscribing witnesses.

WILLIAM THOMAS JAMES.
